UNITED STATES PATENT OFFICE.

FRANK W. THOMAS, OF TOLEDO, OHIO, ASSIGNOR TO THE AUTOPRESS COMPANY, OF NEW YORK, N. Y., A CORPORATION OF NEW YORK.

INKING MECHANISM.

1,135,075.

Specification of Letters Patent. Patented Apr. 13, 1915.

Application filed July 15, 1913. Serial No. 779,075.

To all whom it may concern:

Be it known that I, FRANK W. THOMAS, a citizen of the United States, residing at Toledo, in the county of Lucas, State of Ohio, have invented certain new and useful Improvements in Inking Mechanism; and I do declare the following to be a full, true, and exact description of said invention, such as will enable others skilled in the art to 10 which it appertains to make use of the same.

My invention relates to inking mechanism for printing presses or the like, and particularly to a device by which a more even distribution of ink, according to the requirements of the particular form on the press, 15 may be obtained.

In the usual form of inking mechanism for printing presses, the ink is supplied from an ink fountain having a fountain roller which is turned intermittently to carry ink out of the fountain and the amount of ink permitted to pass from the fountain is controlled by a knife or other adjustable member. The fountain roller is 20 usually of metal, as is the knife also, and it has been found exceedingly difficult to regulate with great nicety the space between this knife and the roller, on which control of the ink supply depends. Such a fountain 25 knife or blade is usually controlled by a series of adjusting screws along its length, by which the operator can adjust the flow of ink but the nice adjustment of these screws required in fine printing is obtained only 30 after considerable care and attention on the part of the operator.

My present invention has for one of its objects devices which obviate the necessity for very exact setting of the knife blade to 40 control the flow of ink.

With this and other objects in view, my invention consists of certain novel features of construction, combination and arrangement of parts as will be more fully described and pointed out in the appended claims.

In the accompanying drawings, Figure 1 represents a longitudinal section on the line 1—1 of Fig. 4, of a printing press mechanism of the type disclosed in the patent to Vierengel, No. 1,004,606, granted October 3, 1911, which mechanism I have selected for purposes of illustration in connection with my novel devices. Fig. 2 represents a 55 section on the line 2—2 of Fig. 1. Fig. 3

represents a plan of Fig. 1. Fig. 4 represents a section on the line 4—4 of Fig. 3. Fig. 5 represents a section on the line 5—5 of Fig. 2.

The corresponding parts are referred to 60 both in the drawings and the specification by similar reference characters.

Referring now to Fig. 1, 10 represents the impression cylinder of the particular type of press which I have chosen for purposes 65 of illustration in connection with my novel inking mechanism. As fully described in the patent to Vierengel referred to, this cylinder has both a reciprocating and a rotating motion. The form bed has attached to 70 it the usual inking plate 11. A form roller carrier 12 is mounted to move with the cylinder 10 and carries form rollers 13—13, and a form distributor roller 14, all as shown in the patent to Vierengel referred 75 to. 15 is an ink fountain of any usual construction provided with a roller 16 arranged to be moved intermittently by any suitable mechanism, preferably the usual ratchet 18 operated by a pawl 17. 23 is a distributor 80 roller continuously rotated by suitable gearing, and 24 is a ductor roller mounted to oscillate between the fountain roller 16 and the distributor roller 23 in any usual manner, and preferably by a cam 27 on the cam 85 shaft 25. A lifting roller 28 is mounted in suitable arms controlled by a cam 26, all in the usual manner, so that the roller 28 contacts with the roller 23 when the ink plate 11 passes from under it to the right 90 of Fig. 1, and is lifted so as to contact with the plate 11 when the plate moves to the left of Fig. 1. The arrangement so far described is of the usual construction 95 and forms no part of my present invention.

In order to illustrate more clearly the purpose of my present invention, I will now point out the defects of the mechanism so far described. Assuming that the form inked by the rollers 13 requires more ink 100 on the right side of Fig. 3 than it does on the left, the operator of the press will endeavor to adjust the screws holding the knife blade (not shown) against the roller 16 so that a greater amount of ink will 105 pass around the roller 16 on its right hand end than on its left. But, as has been pointed out, great nicety in this adjustment requires considerable time, and in the meantime, either too much or too little ink is be- 110

ing supplied to different portions of the form. Then too, in a quick acting press, such as that shown in the patent to Vieren-gel referred to, many sheets may be printed before this adjustment is reached, resulting in considerable wastage, or at least a poor quality of printing for those sheets. To obviate too great refinement in this adjustment, and to obtain the required distribution of the ink in relation to the particular form, I provide a roller 30 of less length than the width of the ink plate 11, and mount this on a shaft 31 so that the roller 30 is movable longitudinally across the path of motion of the plate 11. It will be understood that the roller 30 is also free to rotate on the shaft 31. This shaft 31 is held in a pair of arms 32—32 pivoted on a shaft 33 extending across the side frames of the machine, and held in adjusted position by bolts 34 passing through eyes in the arms 32, into the side frames of the machine. By means of these adjustments, the shaft 31 may be turned around the shaft 33 so that the roller 30, which would usually be a soft roller, and therefore subject to wear, may be brought into proper position to contact with the plate 11 when it is carried into the position shown in Fig. 1.

Preferably I provide mechanism by which the roller 30 may be moved across the plate 11 at the time the roller 30 and the plate 11 are out of contact with each other, this mechanism being arranged so that the roller 30 has no longitudinal motion when it is rolling on the plate 11. As one form of such mechanism, I have shown a worm wheel 35 mounted on a stud 36 attached to a bracket 37 connected to the shaft 33. This worm wheel is driven by a worm 38, on a shaft 39 through suitable gearing, as illustrated, from any convenient portion of the press. Freely mounted on the spindle or stud 36 is an arm 40 connected by a pitman 41 to a sliding member 42 mounted on the shaft 33, this sliding member having a projection 43 engaging with a groove 44 in a member 45 connected to the roller 30. On the worm wheel 35 and in the plane of the arm 40 is a stop pin 46 which may be covered with rubber, fiber or any other suitable material to act as a buffer, and the worm wheel 35 also has a pin 47 to which is connected one end of the spring 48, the other end of the spring 48 being connected to the arm 40, as shown most clearly in Fig. 3. If there were no ink plate 11, the mechanism so far described would never have the position shown in Fig. 3, but the spring 48 would be contracted to hold the arm 40 against the stop 46 so that, as the wheel 35 rotated, the roller 30 would have a continuous longitudinal motion back and forth across the press. When the plate 11 is in contact with the roller 30, however, and especially when the usual sticky print-

ers' ink is on such roller and plate, considerable resistance to longitudinal motion of the roller 30 is set up, and the spring 48 is so designed that this resistance is sufficient to overcome the tension of the spring 48. The roller 30, therefore, rotates, but does not move longitudinally while in contact with the plate 11. During this period, the wheel 35 continues its rotation, thus causing the spring 48 to be stretched. When the plate 11 passes out of contact with the roller 30, however, the spring 48 contracts, drawing the arm 40 against the stop 46 to give it a quick intermittent motion longitudinally while out of contact with the plate 11. When the plate 11 again reengages roller 30, the spring 48 again yields until the plate 11 is out of contact with the roller 30, when the previous action is repeated. In other words, the mechanism which I have shown causes the roller 30 to move by short intermittent steps back and forth across the press, such motion being given, however, only when the plate and roller are out of contact.

Assuming now as before, that the form on the right hand side of Fig. 3 requires more ink than that on the left hand side, and assuming that the fountain blade is adjusted so that substantially a uniform supply is given across the whole length of the roller 16, it will be seen that my roller 30 tends to equalize the distribution of the ink in accordance with the demands of the form. The ink plate 11, through the rollers 24, 23 and 28, will receive from the fountain 15, 100 under the conditions just set forth, a substantially uniform coating of ink throughout its width. This uniform coating will be carried to the rollers 14, and from thence to the form. But the form at the left hand side of Fig. 3 does not require, we will assume, this quantity of ink, whereas the form at the right hand side of Fig. 3 requires more than this quantity of ink. Without the roller 30, under these circumstances, in a short time 110 the plate 11 and the rollers 13 would have accumulated on their left hand ends a considerable quantity of ink, whereas the plate 11 and rollers 13 would have practically no ink on their right hand ends, thus causing 115 the printing to be "muddy" on one side and gray on the other. The roller 30, however, running on the plate 11, will, in the position shown in Fig. 3, take up from the ink plate 11 a quantity of its surplus ink, and as soon as the plate 11 passes out of contact with it, the roller 30 will be moved to say the center of the press, so that when the plate 11 again contacts with it, the quantity 120 of ink on the roller 30 is re-distributed on the plate 11 at a point where there is a relatively small supply of ink, and the plate 11 will take ink from the roller 30 or re-distribute ink thereon according to whether the ink on the plate at that particular zone is 125 130

greater or less than the ink on the roller 30. Similarly, at the next cycle of the press, the roller 30 will have been moved into a position to contact with the right side of the 5 plate 11, and here, under the conditions assumed, the plate 11 will be deficient in ink, and therefore, will take from the roller 30 its surplus ink. In other words, the roller 30 will take up or deposit ink on the plate 11 in 10 accordance with the relation between the quantities of ink on the roller and on that portion of the plate with which it contacts, so that the surplus of ink is carried automatically from the portions of the plate 15 having such surplus to the portions of the plate having a deficiency of supply. Under these circumstances, it will be seen that exact adjustment of the fountain blade is unnecessary.

20 It will be understood that any suitable mechanism other than that which I have chosen for purposes of illustration may be used to move my roller 30 intermittently back and forth across the press.

25 It will be understood that my novel mechanism may be applied to any form of press in which an inking roller is moved alternately into and out of contact with my distributing roller 30 or its equivalent, and 30 that it may be applied equally well to a rotary press, as well as the flat bed press which I have chosen for purposes of illustration.

Having now described my invention what 35 I claim as new and desire to secure by Letters Patent, is as follows:

1. In an inking mechanism, a distributer roller and an ink carrying member arranged to be brought into and out of contact with 40 each other, and means, including a yielding member, to cause said roller to move longitudinally, said yielding member being constructed and arranged to yield when said member and said roller are in contact and 45 to resume normal position when they are out of contact.

2. In an inking mechanism, a distributer roller and an ink carrying member arranged to be brought into and out of contact with 50 each other, and means, including a yielding member, to cause said roller to move longitudinally to and fro, said yielding member being constructed and arranged to yield when said member and said roller are in

contact and to resume normal position when 55 they are out of contact.

3. In an inking mechanism, a distributer roller and an ink carrying member arranged to be brought into and out of contact with each other, and means to give a step by 60 step, longitudinal motion to and fro to said roller.

4. In an inking mechanism, a distributer roller and an ink-carrying member arranged to be brought into and out of contact with 65 each other, and means to traverse said roller longitudinally in a series of steps, each step occurring between successive contacts between said roller and said member.

5. In an inking mechanism, form rollers, 70 a distributer roller, an ink plate arranged to be moved into and out of contact with said form and distributer rollers, and means to move said distributer roller longitudinally only when said plate is out of contact 75 therewith.

6. In an inking mechanism, an ink plate and a distributer roller, arranged to be brought into and out of contact with each other, said roller being shorter than the 80 width of said plate, and means to give said roller a step by step longitudinal motion across the direction of motion of said ink plate.

7. In an inking mechanism, an ink plate 85 and a distributer arranged to be brought into and out of contact with each other, said roller being shorter than the width of said plate, and means to cause said roller to engage with different portions of said plate at 90 successive contacts between said roller and said plate.

8. In an inking mechanism, a distributer roller mounted for longitudinal movement, an ink carrying member arranged to contact therewith, a continuously rotating member and connections, including a spring, between said roller and said rotating member, arranged to give a to and fro longitudinal motion to said roller, said spring being 95 adapted to yield when said ink carrying roller and said ink carrying member are in contact and to resume its normal position 100 when they are out of contact.

FRANK W. THOMAS.
